(57) CLAIM

The ornamental design for a buckle, as shown and described.

DESCRIPTION

FIG. 1 is a first perspective view of a buckle showing my new design;

FIG. 2 is a second perspective view thereof;

FIG. 3 is a front view thereof;

FIG. 4 is a rear view thereof;

FIG. 5 is a left side view thereof, a right side view being symmetrical to the left side view;

FIG. 6 is a plan view thereof;

FIG. 7 is a bottom view thereof;

FIG. 8 is a cross-sectional view thereof along the line 8-8 in FIG. 3;

FIG. 9 is a first perspective view of a male body of the buckle;

FIG. 10 is a second perspective view thereof;

FIG. 11 is a first perspective view of a female body of the buckle; and,

FIG. 12 is a second perspective view thereof.

Outer thick lines indicate outer shapes of the buckle, and inner thin lines indicate inner contour of the buckle for illustration purpose.
